UNITED STATES PATENT OFFICE.

FRANK L. ROSS, OF CINCINNATI, OHIO, AND JAMES T. EARLE, OF LATONIA, JOSHUA J. GOOD, OF HARRODSBURG, AND HOPE REDMON, OF CYNTHIANA, KENTUCKY, ASSIGNORS TO BLANCHE M. WILSON, OF CINCINNATI, OHIO.

AUTOGRAPHIC REGISTER.

SPECIFICATION forming part of Letters Patent No. 663,667, dated December 11, 1900.

Application filed December 18, 1899. Serial No. 740,704. (No model.)

To all whom it may concern:

Be it known that we, FRANK L. ROSS, residing at Cincinnati, in the county of Hamilton and State of Ohio, and JAMES T. EARLE, residing at Latonia, in the county of Kenton, JOSHUA J. GOOD, residing at Harrodsburg, in the county of Mercer, and HOPE REDMON, residing at Cynthiana, in the county of Harrison, State of Kentucky, citizens of the United States, have invented certain new and useful Improvements in Autographic Registers, of which the following is a specification.

Our invention relates to an improvement in autographic registers having for an object the production of a device in which the paper strip will be fed over a pair of revoluble folding-cylinders journaled in a frame and geared together. The original record and copy are delivered exteriorly, the triplicate copy folded by the cylinders into a receiving-compartment and filed upon a paper-holding rack detachably located therein.

Our invention further comprises means for accomplishing these results in a simple and efficient manner, the features of which are more fully set forth in the description of the accompanying drawings, making a part of this specification, in which—

Figure 1 is a central vertical section of our device. Fig. 2 is a perspective view of the holding-rack. Fig. 3 is a plan view of the clamping mechanism. Fig. 4 is a perspective view of the folding-cylinders and strippers detached from the frame. Fig. 5 is a plan view of the spring-controlled stripping device. Fig. 6 is an end view, partly in section, of one of the cylinders. Fig. 7 is a similar view of the opposite end of the cylinder. Fig. 8 is a similar view to Fig. 6, showing the clamp-arm in operation.

A represents the box or frame, in the front portion of which are journaled paper-rolls 1, 2, and 3. The strips from rolls 1 3 pass over carrier-roll a , and the strip from roll 2 passes over roll a' . They are fed in this order over the writing tablet or support b opposite the open section B on the top of the frame for writing. The carbon pieces $c c'$ are supported

on this tablet respectively between the three paper strips in the usual manner. The two upper strips are delivered exteriorly between rolls $d d'$, having the end gear-wheels $e e'$ in mesh with each other. One of these wheels e' has a handle H for revolving these rolls and for operating the entire device. The record-copy is delivered under the roller d' and over carrier-roll f to the folding-cylinders. These cylinders C D have end gear-wheels $g g'$ in mesh with each other, and cylinder D has a gear-wheel g^2 in mesh with an intermediate gear-wheel h , meshing with the gear-wheel e' , from which it receives power. These revoluble parts are all suitably journaled in the frame A. Each cylinder has in its face a tongue $E E'$ and a groove $F F'$, running parallel to the axle and cam-guide groove $G G'$ transverse thereto. These tongues and grooves are so disposed that the tongue on each cylinder will engage with the groove on the opposite cylinder during the cylinder revolution, thereby tucking the paper extended over the tongue, thereby forming a fold into the receiving-groove, where the fold is automatically caught by the clamping instrumentalities, which are as follows:

h^2 represent the axles of the cylinders. Upon these are mounted the clamping-arms I by means of ears $i i'$. (See Fig. 3.) On the axles are stop-collars 4 5 to prevent endwise movement of the clamping-arms. The clamping-arms extend out radially to the grooves in the faces of the cylinders. The length of the movement of the clamping-arm is of course limited by the width of the groove.

j represents a spring wound around the axle secured thereto at one end and the other end bearing against the arm and forcing it normally against one wall, as shown in Fig. 6. Each arm is provided with a hook projection J.

K represents a tripping-lever (see Fig. 5) having one bearing in the cylinder-head k and piercing the opposite cylinder-head k' and projected beyond the said head. This lever passes through the hook portion J of arm I and has a cam-lug L at this point adapted

to engage the hook and deflect the clamping-arm when the tripping-lever is pressed in endwise.

l represents a spring wound around the tripping-lever for retracting it.

Upon the frame opposite the cylinder-heads is cast or otherwise attached a cam-ledge l, which engages the bevel ends m m' when they are brought into position by the cylinder 10 revolution. As the strip to be folded is fed between the cylinders the tongue on cylinder C tucks the paper into the groove on cylinder D. The ledge then trips the tripping-arm on cylinder D, which actuates the clamping-arm 15 and clamps it down upon the fold of paper tucked into the groove. The cylinder D carries this fold of the paper to the front of the box and the cylinder C at the appropriate interval forms a fold and carries it to the opposite end of the receptacle M. The following instrumentalities are provided for filing these folds:

G G' represent the transverse cam-grooves in the faces of the cylinders.

25 O P represent stripping devices, one mounted upon each side of the pair of folding-cylinders. The stripper O in front of the pair of cylinders is mounted in a hollow standard o and rests upon spring o'. The stripper P 30 is mounted on a cross-bar p, resting on springs p', sleeved upon standards. The reason why two standards are used at the rear is to provide access and egress to the paper-holding rack Q, to be later described. The strippers 35 O P rest normally in contact with the respective cylinder-faces, being slightly compressed on their springs and in the line of travel of the transverse cam-grooves G G'. The strippers are provided with orifices q q', normally 40 engaging the ends of pins r r', projected from opposite ends of holding-rack Q. The grooves G G' cross the grooves F F'. Just before cylinder D has carried the fold of the paper to the extreme front of the receiving-compartment the nose of the stripper enters the 45 groove and the stripper extends under spring-pressure, and the travel of the cylinder brings the fold under the nose of the stripper at the deepest portion of the camway, from which 50 point it is slowly depressed again to normal position on the face of the cylinder, carrying down with it the said fold and pressing it over the end of filing-pin r'. The cylinder C folds and files the opposite end of the paper 55 in like manner.

In order to readily take out and replace the holding-rack, we provide the following instrumentalities:

S represents a compartment for the reception of the holding-rack Q. An open space s is provided in the base of said frame immediately under the cylinders for the longitudinal removal of the rack with its filing-pins.

T represents a plate having the ear t, through 65 which passes eccentric lever U, journaled in the frame of the device.

u represents the handle of a door for access

to compartment S. The holding-rack is slid longitudinally into the compartment S upon plate T. The eccentric lever is turned, raising the rack in a vertical plane until its filing-pins enter the orifices q q'. This is for the purpose of raising and lowering the detachable rack in such manner that the pins shall be horizontally under and rising vertically 75 into position. A single stripper and a single filing-pin at one end of the paper-compartment M would operate, though less satisfactorily, as it would leave loose folds at one end of the rack, and it is obviously of greater 80 utility to have the folds compressed into position at each end of the rack. Various modifications for actuating the clamping-arms, strippers, and for operating the holding-rack could readily be devised by a skilful mechanic familiar with our invention, and we do not wish to be limited to any specific features not herein expressly claimed.

Having described our invention, we claim—

1. In an autographic register the combination of a pair of revoluble folding-cylinders journaled in a frame and geared together, a tongue and groove in each cylinder, means for revolving said cylinders whereby the tongue of each cylinder engages the groove 95 of its coaxing cylinder during each revolution, a spring clamping member in each groove having an actuating-bar projected beyond the end of its cylinder, means mounted on the frame adapted to engage said bar and depress 100 said member during the cylinder revolution, a cam-groove in the face of each cylinder, and a spring-controlled stripping device supported upon each side of the pair of cylinders 105 engaging the faces thereof in the path of travel of the cam-grooves, substantially as described.

2. In an autographic register the combination of a pair of revoluble folding-cylinders journaled in a frame and geared together, a tongue and groove in each cylinder, means 110 for revolving said cylinders whereby the tongue of each cylinder engages the groove of its coaxing cylinder during each revolution, a spring clamping member in each groove having an actuating-bar projected beyond the 115 end of its cylinder, means mounted on the frame adapted to engage said bars and depress said clamping members during the cylinder revolution, a cam-groove in the face of each cylinder, a spring-controlled stripping device 120 supported upon each side of the pair of cylinders engaging the lower portion of their faces in the path of travel of the cam-grooves and a holding-rack having filing-pins located under the strippers, substantially as described.

3. In an autographic register the combination of a pair of revoluble folding-cylinders journaled in a frame and geared together, a tongue and groove diametrically opposed in each cylinder, means for revolving said cylinders whereby each tongue engages the groove of its coaxing cylinder during each revolution, a spring clamping member in each groove, an actuating-bar therefor projected 130

beyond the end of its cylinder, means mounted on the frame adapted to engage said bars and depress said members during the cylinder revolution, a cam-groove in the face of one cylinder, and a spring-controlled stripping device supported upon one side of said cylinder engaging the face thereof in the path of travel of said cam-groove, substantially as described.

10 4. In an autographic register the combination of a pair of revoluble folding-cylinders journaled in a frame and geared together, a tongue and groove in each cylinder, means for revolving said cylinders whereby each 15 tongue engages the groove of its coacting cylinder during each revolution, a spring clamping member in each groove, an actuating-bar therefor projecting beyond the end of its cylinder, means mounted on the frame adapted 20 to engage said bars, a cam-groove in the face of one cylinder, a spring-controlled stripping device supported upon one side of the pair of cylinders engaging the face thereof in the path of travel of the cam-groove and a holding-rack provided with a filing-pin located 25 under the stripper, substantially as described.

5. In an autographic register the combination of a pair of revoluble folding-cylinders journaled in a frame and geared together, a 30 tongue and groove in each cylinder, means for revolving said cylinders whereby each tongue engages the groove of its coacting cylinder during each revolution, a spring clamping member in each groove, an actuating-bar 35 for each clamping member projected beyond the end of its cylinder, means mounted on the frame adapted to engage said bar, a transverse cam-groove in the face of each cylinder, a

spring-controlled stripping device supported upon each side of said cylinders engaging the 40 faces thereof in the line of travel of the cam-grooves, orifices in said strippers and a holding-rack supported under the cylinders having filing-pins normally engaging the orifices in the strippers, substantially as described. 45

6. In an autographic register the combination of a pair of revoluble folding-cylinders journaled in a frame and geared together, a tongue and groove in each cylinder, means for revolving said cylinders whereby each 50 tongue engages the groove of its coacting cylinder during each revolution, a spring clamping member in each groove, an actuating-bar for each arm projected beyond the end of each cylinder, means mounted on the frame adapted 55 to engage said bars, a transverse cam-groove in the face of each cylinder, a spring-controlled stripping device supported on each side of said cylinders engaging the faces thereof in the path of travel of the cam-grooves, an 60 orifice in each stripper, a detachable holding-rack supported under said cylinders having filing-pins normally engaging the orifices in the stripper, and means for bodily raising and lowering said plate into and out of position, substantially as described. 65

In testimony whereof we have hereunto set our hands.
